UNITED STATES PATENT OFFICE.

WILLIAM E. SPARKS, OF NEW BRITAIN, CONNECTICUT, ASSIGNOR TO THE
NASHUA LOCK COMPANY, OF NASHUA, NEW HAMPSHIRE.

DESIGN FOR A HINGE.

SPECIFICATION forming part of Design No. 15,012, dated May 20, 1884.

Application filed February 4, 1884. Term of patent 14 years.

To all whom it may concern:

Be it known that I, WILLIAM E. SPARKS, a citizen of the United States, residing at New Britain, in the county of Hartford and State of Connecticut, have invented and produced a new and original Design for Hinges, of which the following is a specification, reference being had to the accompanying drawings, forming part thereof.

Figure 1 is a front elevation of my newly-designed hinge, and Fig. 2 is a plan view of one member of said hinge.

The leading feature of my design for a hinge consists in the shape or configuration of the knuckle, which is of angular contour in plan view, either with four or six faces, but preferably with only four, as shown in Fig. 2.

The ornamental portion of the design is shown in the accompanying drawings, aside from the general shape of the knuckles, and I do not wish to be understood as laying any claim to the same, not being of my invention or production.

A A designate the respective knuckles for the hinge-leaves B B. These knuckles, as shown in Fig. 2, are of angular contour in plan view, the same being substantially a square figure with the sides standing obliquely

to the inner face of the hinge-leaf B. This position of the square hub with reference to 30 the hinge-leaf brings two faces of each knuckle clearly exposed when viewed in front elevation, with the hinge-leaves swung open, as shown in Fig. 1. This enables the various faces upon the sides of the angular knuckles to 35 be readily exposed to view, and clearly show whatever ornamentations may be placed thereon, thereby presenting a very different effect to the eye from that of a hinge with round 40 knuckles having no flat faces for ornamenta- 40 tion.

I claim—

1. The design for a hinge herein shown and described, the same consisting of the knuckles having an angular contour in plan view, and 45 with the leaf B extending therefrom.

2. The design for a hinge herein shown and described, the same consisting of the leaf B and knuckle A, said knuckle being of a square form in plan view, and with its sides oblique 50 to the inner face of the leaf.

WILLIAM E. SPARKS.
